UNITED STATES PATENT OFFICE

171,033

DISPLAY RACK OR THE LIKE

Lawrence Wright Gordon, Stockton, Calif.

Application March 1, 1952, Serial No. 18,750

Term of patent 14 years

(Cl. D80—9)

To all whom it may concern:

Be it known that I, Lawrence Wright Gordon, a citizen of the United States and a resident of Stockton, in the county of San Joaquin and State of California, have invented a new, original, and ornamental Design for a Display Rack or the like, of which the following is a specification, reference being had to the accompanying drawing forming a part thereof.

Figure 1 is a front perspective view of a display rack or the like, showing my design;

Figure 2 is a side elevational view thereof.

I claim:

The ornamental design for a display rack or the like, substantially as shown.

LAWRENCE WRIGHT GORDON.
